UNITED STATES PATENT OFFICE

JACK FAYETTE WEST, OF CANTON, GEORGIA, ASSIGNOR TO DRAPER CORPORATION, OF HOPEDALE, MASSACHUSETTS, A CORPORATION OF MAINE

FILLING FORK AND GRID CLEANER

Application filed December 1, 1930. Serial No. 499,202.

This invention has for its object to provide a simple and efficient means for keeping the tines and grid bars of the filling fork mechanism of an automatic loom clear from 5 fly, lint, and other foreign matter.

The invention has for its further object to provide means for preventing bouncing or undue vibration of the filling fork so as to insure its proper cooperation with the weft 10 hammer or other operating mechanism.

The invention has for its further object to provide means for preventing a broken or unduly slack filling end from being thrown around the tines of the fork so as to interfere 15 with the proper action thereof.

These and other objects and features of the invention will appear more fully from the accompanying description and drawings and will be particularly pointed out in the claims.

As the invention is concerned entirely with the filling fork mechanism of an automatic loom, and as the construction and operation of such mechanisms as well as of the looms in which they are embodied are all well 20 known and familiar to those skilled in the art, it is only necessary here to illustrate portions of an ordinary type of loom and an ordinary type of filling fork mechanism, together with a preferred form of the present 25 invention applied thereto.

In the drawings:

Fig. 1 is a side elevation partially in vertical cross section of a portion of a loom, a filling fork mechanism, and a preferred form 30 of the present invention embodied therein.

Fig. 2 is a top plan view on a larger scale of a portion of the construction shown in Fig. 1.

The loom shown is of an ordinary construction including side frames such as 1 connected at the front and at the top by the usual breast beam 2 and comprising the lay swords such as 3 carrying the lay 4 swinging toward and from the breast beam in the usual manner 40 during the weaving operation.

As is well known, such looms are commonly rendered automatic by embodying therein a so-called filling fork mechanism which acts upon breakage or failure of the 45 running filling to effect a change in the oper-

ation of the loom, such, for example, as either the stopping of the loom or the automatic replenishment of the running filling supply. Such a filling fork mechanism usually comprises two main elements, namely, a grid carried by the lay and in front of which lies the path of the filling from the shuttle to the cloth and a filling fork pivoted on a fork slide carried by the breast beam. 55

In the form illustrated, the grid is shown 60 as comprising a plurality of spaced and generally U-shaped bars 5 connected at their free rear ends to supports 6 and thereby secured to the lay so that the front portions of the bars stand perpendicularly to the raceway 7. 65 This grid is usually mounted in a recess 8 formed in the lay adjacent the edge of the cloth.

A filling fork slide 9 is mounted to slide 70 forward and rearward on the breast beam opposite the grid. At its rearward end it has pivoted thereto at 10 a fork comprising the depending tines 11 and the forwardly extending looped end 12. A weft hammer 13 is fulcrumed at 14 on the loom frame and is given 75 a forward and backward swinging movement during the operation of the loom, the forward movement taking place at alternate picks all in the well-known manner. This weft hammer at its upper end has pivoted 80 thereto a hook 15 which, when the weft hammer swings rearward, passes beneath the looped end 12 of the fork so that if the fork engages the hook, the weft hammer on its forward movement moves the entire fork 85 slide forward and this movement of the fork slide is utilized all in the familiar manner to effect the desired change in the operation of the loom, such as the stopping of the loom or the replenishment of the filling. 90

Normally the filling is laid fairly taut in front of the grid bars 5 as the shuttle is picked to the detecting side of the loom, or that side where the filling fork mechanism is located. Consequently as the lay beats up, and the tines 11 of the fork tend to pass between the bars 5 of the grid, the filling will cause the fork to rock and prevent its looped end 12 from being caught by the hook 15. 95 If, however, the filling is absent, due to ex- 100

haustion or breakage, the filling fork will not rock and consequently the hook 15 will catch the looped end 12 and the fork slide will be moved forward.

It is very essential that the tines of the fork and the bars of the grid be kept clear from fly, lint, and other foreign material so as to insure their proper cooperative action. Furthermore, since the lay beats up with a sudden blow and since the filling fork must be very light, it frequently happens that the blow given to the filling fork by the taut filling and the jar of the parts causes the filling fork to vibrate or bounce so that it fails properly to cooperate with the hook 15. Furthermore, if the filling breaks adjacent the end of the shuttle, it may snap or be thrown around the tines of the fork, thus interfering with the proper action of the fork. The present invention obviates all of these difficulties.

In the preferred form of the invention, a brush comprising a base 17 and bristles 18 is supported in front of the fork with the bristles facing the tines and is moved into engagement with the fork tines when the lay beats up on a detecting pick. The bristles are relatively soft and sufficiently spaced so that they do not interfere with a normally positioned filling. Preferably the brush is adjustably mounted by the bolt 19 in a slot 20 on an arm 21 secured to the weft hammer 13. The weft hammer, it will be remembered, swings rearward as the lay beats up and thus is available for giving the required movement to the brush.

It will thus be seen that as the lay beats up and the fork tines come into cooperative relation with the grid bars, the brush engages the tines and grid bars and, when it swings forward, carries with it any lint, fly, or foreign matter, thus constantly maintaining the tines of the filling fork and the bars of the grid clear. It will also be seen that as the brush comes into engagement with the fork tines just as they are cooperating with the grid bars, the brush acts to steady the fork and prevent it bouncing or vibrating so that the proper cooperation of the fork with the hook 15 of the weft hammer is insured. It will also be seen that the brush engaging the fork tines prevents any broken filling from being thrown or snapped around the fork tines so as to interfere with the proper action of the fork.

There is thus provided a very simple and efficient mechanism readily attached to existing looms, economical of manufacture and maintenance, which acts to obviate the objections heretofore noted.

Having thus described the invention, what is claimed as new, and desired to be secured by Letters Patent, is:

1. In a loom having a filling fork pivoted on a fork slide carried by the breast beam

and a grid carried by the lay and cooperating with the fork, the combination of a brush and means for supporting the brush in front of the fork with the bristles facing the tines and for moving the brush into engagement with the fork tines when the lay beats up on a detecting pick, thereby to steady the fork, prevent filling from being thrown around the fork tines and clear the tines.

2. In a loom having a filling fork pivoted on a fork slide carried by the breast beam and a grid carried by the lay and cooperating with the fork, the combination of a brush and means for supporting the brush in front of the fork with the bristles facing the tines and for moving the brush into engagement with the fork tines and grid bars when the lay beats up on a detecting pick and brings the said tines and bars into cooperative relation, thereby to steady the fork, prevent filling from being thrown around the fork tines and clear the tines and bars.

3. In a loom having a filling fork pivoted on a fork slide carried by the breast beam, a grid carried by the lay and cooperating with the fork, and a weft hammer extending in front of and moving toward and from the fork on alternate picks, the combination of a brush and means for supporting the brush on the weft hammer in front of the fork with the bristles facing the tines whereby the brush is brought into engagement with the fork tines when the lay beats up on a detecting pick and acts to steady the fork, prevent filling from being thrown around the fork tines and clear the tines.

4. In a loom having a filling fork pivoted on a fork slide carried by the breast beam, a grid carried by the lay and cooperating with the fork, and a weft hammer extending in front of and moving toward and from the fork on alternate picks, the combination of a brush and means for supporting the brush on the weft hammer in front of the fork with the bristles facing the tines, whereby the brush is brought into engagement with the fork tines and grid bars when the lay beats up on a detecting pick and brings the said tines and bars into cooperative relation, thereby to steady the fork, prevent filling from being thrown around the fork tines and clear the tines and bars.

In testimony whereof, I have signed my name to this specification.

JACK F. WEST.
